UNITED STATES PATENT OFFICE.

ALBERT A. BRUDER, OF HOLLY, MICHIGAN.

FURNACE OR STOVE.

Application filed October 20, 1921. Serial No. 509,024.

To all whom it may concern:

Be it known that I, ALBERT A. BRUDER, a citizen of the United States of America, residing at Holly, in the county of Oakland and State of Michigan, have invented certain new and useful Improvements in Furnaces or Stoves, of which the following is a specification, reference being had therein to the accompanying drawing.

10 This invention relates to furnaces or stoves of that class of the magazine type in which a large quantity of fuel may be placed to be gradually burned and thus obviate the necessity of continuously supplying the furnace or stove with fuel.

20 The primary object of my invention is to provide a heating apparatus, either in the form of a furnace or a stove, wherein the smoke and gases are led in proximity to the fire or live coals of the furnace or stove to be consumed thereby and increase the heating efficiency of the furnace or stove.

25 Another object of my invention is to provide a furnace or stove with a large heat radiating drum constructed to afford a large heat radiating surface and retard, to a certain extent, the exhaust gases of the furnace or stove so that the same may be burned and thus prevent products of combustion from 30 being carried off in the final exhaust of the furnace or stove.

35 As a furnace, the heating apparatus may be located in a furnace casing or shell and have cold air directed against the heating drum of the apparatus. As a stove, the heating drum is exposed to the atmosphere to heat surrounding air, and in either instance a maximum heat is produced by reason of all products of combustion being consumed. With a good grade of fuel there is 40 very little residue and with a low grade of fuel the same is burned until its full caloric value is obtained.

45 The construction of my heating apparatus will be hereinafter described and then claimed, and reference will now be had to the drawing, wherein

50 Figure 1 is a vertical cross sectional view of the stove, partly in elevation, showing by dot and dash lines the outline of a portion of a furnace shell in which the stove may be located;

55 Fig. 2 is a side elevation of the stove partly broken away and partly in section; and Fig. 3 is a plan of the stove, on a smaller scale.

In the drawing, the reference numeral 1 denotes a substantially rectangular base which provides an ash chamber 2 either for the furnace or stove, and the front wall of the base has a conventional form of ash door 3 provided with a damper 4. The top of the base has an opening 5 for a rocker or tiltable grate 6 which may be actuated from the front wall of the base 1, although various types of grates may be used in the heating apparatus.

Mounted on the base 1 is the lower laterally flanged end of a fire box 7 having an upper cylindrical end 8 on which is mounted 70 and suitably secured thereto a cover 9 having its front wall provided with an air intake member or opening 10 and a doorway frame 11. The doorway frame 11 is directly below the air intake member 10 and said doorway frame has a conventional form of door 12.

80 Suspended in the cover 9 or otherwise mounted therein is a dome or hood 13 which has its walls in spaced relation to the cover 9 and its lower end extending into the upper end 8 of the fire box 7 so as to provide a comparatively narrow passage between the cover 9, the upper end 8 of the fire box 7 and the dome. The front wall of the dome 13 has a frame 14 adjoining the doorway frame 11 and consequently coal or other fuel 85 15 can be placed in the dome 13. The walls of the dome 13, adjacent the top thereof have a plurality of exhaust openings 16 90 through which smoke, gases and other unconsumed matter is adapted to pass and enter the passage 17 leading to the fire box 7, said passage receiving cold air from the member 10.

95 Between the upper end 8 of the fire box 7 and the base 1 there is a substantially semi-circular heat radiating drum composed of angularly disposed parallel walls 18 and 19, the wall 18 being integral with the upper 100 end 8 of the fire box 7 and the wall 19 integral with the lower end thereof; both of said walls having curved outer flanged edges 20 connected by stove bolts 21 or other fastening means. The walls 18 and 19 therefore 105 cooperate in providing a combustion chamber 22 that is substantially semi-circular in plan and disposed at an acute angle to the base of the stove, the drum structure being somewhat as a skirt about the greater part 110 of the fire box.

Mounted in the upper end of the chamber

22 is a semi-circular baffle or deflector 23 which is supported by inwardly projecting arms 24 mounted between or suitably attached to the flanged edges 20 of the walls 18 and 19. The wall 18, intermediate its ends, has an exhaust stack or flue 25, which may be provided with a conventional form of damper (not shown). Any suitable damper or damper operating mechanism 10 may form part of the furnace or stove in order that the operation of the furnace or stove may be conveniently controlled, but such damper or damper operating mechanism forms no part of the present invention.

15 When a fire is started in the fire box 7 the live coals or fuel will be at the lower end of the chamber 22 and such live coals will be exposed in said chamber and at the lower end of the passage 17, so that the down draft 20 of smoke and gases must impinge against such live coals and be burned, if not actually consumed, by the live coals. The downdraft of smoke and gases serves to protect the wall 18, at its juncture with the upper end 8 of 25 the fire box 7, from being burned out or subjected to such heat as may distort the wall 18, and such smoke and gases as is not consumed by the live coals ascends in the chamber 22, but is retarded in its ascension or 30 passage through the chamber by the baffle 23.

By reference to Figs. 1 or 2, it will be noted that the edges of the baffle 23 are in proximity to the walls 18 and 19 and for practical purposes the space between the 35 edges of the baffle 23 and the walls 18 and 19 should not be greater in area than the cross sectional area of the flue 25, so that there will be at all times an exit for the smoke and gases. However, the baffle 23 will maintain 40 somewhat of a circulation of smoke and gases in the chamber 22 so that all products of combustion will be brought into intimate relation to the live coals to be consumed thereby. In this manner an intense heat 45 will be produced at the bottom of the chamber 22, and as the live coal and products of combustion are consumed the coal within the dome or magazine of the stove will feed downwardly and supply the fire-box 7.

50 The heating apparatus has been illustrated as a stove in Fig. 2 and its use as a furnace is suggested by the dot and dash line inclos-

ure of Fig. 1, it being understood that the door frames of the stove will be extended to meet the furnace casing so that fuel may be 55 placed in the stove and ashes removed therefrom.

I attach considerable importance to the shape of the heat radiating drum as it affords a large heated area with which cold air 60 may contact and be heated thereby, and furthermore, that with the stove in full operation it is practically impossible for combustible matter to escape from the stove without being burned. All of this contributes to the high heating efficiency of the apparatus, and while in the drawing there is illustrated a structure which has been put into practice, nevertheless, I do not care to confine my invention to any details other than 65 defined by the appended claims.

What I claim is:—

1. A magazine stove comprising a fire box having a substantially semi-circular heating radiating drum formed by parallel walls disposed at an angle to the vertical axis of the stove, said fire box having an upper cylindrical end supported by one of the walls of said drum, an exhaust flue for said drum, a cover mounted on the cylindrical end of said fire box and provided with an air inlet opening, and a dome suspended in said cover and having a doorway at said cover so that fuel may be placed in said dome, said dome cooperating with said cover in providing a passage 80 opening into said drum, and said drum having openings communicating with said passage.

2. A magazine stove as called for in claim 1, and a semi-circular deflector in the extreme outer portion of said drum forming a baffle, particularly at the exhaust flue of said drum.

3. A magazine stove as called for in claim 1, wherein the air inlet opening of said cover is formed by an air intake member extending from the front of said cover to the back thereof.

In testimony whereof I affix my signature in presence of two witnesses.

ALBERT A. BRUDER.
